(57) **CLAIM**

The ornamental design for a light rail, as shown and described.

DESCRIPTION

FIG. 1 is a bottom perspective view of an embodiment of a light rail.

FIG. 2 is a left elevation view of the light rail of FIG. 1.

FIG. 3 is a right elevation view of the light rail of FIG. 1.

FIG. 4 is a front elevation view of the light rail of FIG. 1.

FIG. 5 is a rear elevation view of the light rail of FIG. 1.

FIG. 6 is a bottom plan view the light rail of FIG. 1.

FIG. 7 is a bottom perspective view of another embodiment of a light rail.

FIG. 8 is a left elevation view of the light rail of FIG. 7.

FIG. 9 is a right elevation view of the light rail of FIG. 7.

FIG. 10 is a front elevation view of the light rail of FIG. 7.

FIG. 11 is a rear elevation view of the light rail of FIG. 7.

FIG. 12 is a bottom plan view the light rail of FIG. 7.

FIG. 13 is a bottom perspective view of yet another embodiment of a light rail.

FIG. 14 is a left elevation view of the light rail of FIG. 13.

FIG. 15 is a right elevation view of the light rail of FIG. 13.

FIG. 16 is a front elevation view of the light rail of FIG. 13.

FIG. 17 is a rear elevation view of the light rail of FIG. 13; and,

FIG. 18 is a bottom plan view the light rail of FIG. 13.

The light rail is shown broken away in the middle of the design to indicate no specific length. Portions or features of the light rail not shown in the drawings form no part of the claimed design. The broken lines in the drawings illustrating portions of the light rail form no part of the claimed design.
